(57) **CLAIM**

The ornamental design for a flipping egg holder, as shown and described.

DESCRIPTION

FIG. 1 is a perspective view of a flipping egg holder showing my new design;

FIG. 2 is a bottom perspective view thereof;

FIG. 3 is another front perspective view of the flipping egg holder in an alternate configuration with the two shelves in a slanted position;

FIG. 4 is a front view thereof;

FIG. 5 is a back view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate features of the flipping egg holder that form no part of the claimed design.
